Primary Examiner — Shannon W Morgan*Assistant Examiner* — Terilyn Davis(74) *Attorney, Agent, or Firm* — ScienBiziP, P.C.(57) **CLAIM**

The ornamental design for a rice bucket, as shown and described.

DESCRIPTION

FIG. 1 is a front, right and top perspective view of a rice bucket, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1; and,

FIG. 10 is another front, right and top perspective view of the rice bucket in another state.

The broken lines shown in the drawings are included for the purpose of illustrating portions of the rice bucket that form no part of the claimed design. In addition, the dot-dash broken lines in FIGS. 1 and 9 depict the boundaries of the enlargements that form no part of the claimed design.
